UNITED STATES PATENT OFFICE.

SHEDRACH D. NORTHCUTT, OF LOS ANGELES, CALIFORNIA.

CARRIER-TRACK CABLE CURVE.

SPECIFICATION forming part of Letters Patent No. 415,551, dated November 19, 1889.

Application filed August 31, 1889. Serial No. 322,623. (No model.)

To all whom it may concern:

Be it known that I, SHEDRACH D. NORTHCUTT, a citizen of the United States, residing at Los Angeles, in the county of Los Angeles and State of California, have invented certain new and useful Improvements in Carrier-Track Cable Curves, of which the following is a specification, reference being had therein to the accompanying drawings, in 10 which—

Figure 1 is a perspective view of a portion of an elevated cable-railway provided with my improvement, and Fig. 2 a vertical transverse sectional view taken through the curved 15 guide which envelops the cable.

The object of the invention essentially is to produce an exceedingly simple device for maintaining the curvature of stationary cable or wire-rope railways adapted to support and 20 transport suitable wheeled cars or carriers which travel upon or are suspended from the said cable or cables, as will more fully appear hereinafter.

The improvement is designed principally 25 for use on elevated railways; but it may be employed upon others with equal advantages.

In the drawings, *a* designates a stationary cable which is drawn taut and attached to suitable supports (not shown) at its ends.

30 Upon this cable is adapted to travel any suitable wheeled carrier or car for the purpose of transporting freight of all kinds.

In erecting this class of cable-tracks it frequently becomes necessary to deflect or turn 35 them out of their direct lines, and to effect-

ually retain the curvature of the cables when thus deflected is the special object of this invention. I employ a stiff strip of sheet metal *b*, of suitable length and width, and envelop the cable with it, the two depending longitudinal edges of the plate being pressed close together, so as to closely clamp the cable. The folded strip, when thus folded and placed over the cable, may be bent and curved to any desired degree of curvature. To support the 45 cable and its guide, I employ suitable posts *c*, provided at their upper ends with U-shaped clamping-plates *d*, which embrace the depending edges of the guide *b* and are bolted thereto. 50

This invention may be employed with equal advantage whether two or more cables are employed, as is evident.

Having thus fully described my invention, what I claim is— 55

The combination of stationary cable *a*, plate *b*, folded or bent longitudinally and placed over the said cable so as to wholly envelop and clamp the same, the two longitudinal depending edges of the plate being 60 pressed closely together, and the supports and U-shaped clamps embracing and bolted to the said depending edges of the plate *b*, substantially as described.

In testimony whereof I have affixed my signature in presence of two witnesses.

SHEDRACH D. NORTHCUTT.
